[57] CLAIM

The ornamental design for joystick control for video
games and computer systems, as shown and described.

DESCRIPTION

FIG. 1 is a front elevation of a joystick control for video
games and computer systems showing my new design;
the rear elevation being a mirror image thereof;

FIG. 2 is a top plan view thereof;

FIG. 3 is a bottom plan view thereof;

FIG. 4 is a left side elevation thereof; and

FIG. 5 is a right side elevation thereof.

FIG. 2

FIG. 4

FIG. 1

FIG. 5

FIG. 3
